[57] CLAIM

The ornamental design for a golf cart, as shown and described.

DESCRIPTION

FIG. 1 is a front perspective view of a golf cart showing my new design;
FIG. 2 is a front elevational view thereof;
FIG. 3 is a left-side elevational view thereof;
FIG. 4 is a rear elevational view thereof;
FIG. 5 is a right-side elevational view thereof;
FIG. 6 is a top plan view thereof;
FIG. 7 is a bottom plan view thereof;
FIG. 8 is a left side elevational view thereof in its transition to a folded condition;
FIG. 9 is a left side elevational view thereof in a folded condition; and,
FIG. 10 is a front perspective view thereof, the broken lines are for illustrative purposes only and form no part of the claimed design.
